UNITED STATES PATENT OFFICE.

SIMON E. SCHROEDER, OF NEWTON, IOWA.

WRINGER.

Original application filed March 14, 1925, Serial No. 15,434. Divided and this application filed August 16, 1926. Serial No. 129,620.

The object of my invention is to provide a wringer structure in which the end guards for the rollers may be readily assembled with the main frame and held in place without bolts or screws, the construction being such that the end guards may be readily removed and replaced.

The invention herein specifically claimed has been divided out of my pending application Serial Number 15,434 filed March 14, 1925, now Patent 1,645,297, patented Oct. 11, 1927.

The accompanying drawings illustrate my invention:

Fig. 1 is a vertical transverse medial section, of a wringer embodying my invention, the top roller and associated parts being omitted; Fig. 2 a section on line 2—2 of Fig. 1; and Fig. 3 a fragmentary side elevation with the top roller in place.

In the drawings 10 indicates an inverted base channel from the ends of which rise the end channels 11, each comprising the outer wall 12, the side walls 13, 13 and the inverted vertical lips 14, 14 the inner edges of which are spaced to receive the ends of the shafts of the rollers 15.

In order to guard the ends of the rollers and prevent articles from passing off over the ends of the rollers and in order to guide expressed water inwardly onto the adjustable reversing drain pan, I provide, at each end of the roller, a readily removable and replacable guard comprising a slotted plate

20 the inner vertical edges of which are bent to form hooks 21 which embrace the inner edges of lips 14, and the outer and lower edges of which are turned substantially at right angles to the plate to form vertical

flanges 22 overlying the ends of rollers 15, and the arcuate lower flange 23 underlying the adjacent end of the lower roller.

Clothes guides, directing garments to the crotch between rollers 15, are formed by plates 30 each having its ends upturned at 31 pivoted, by rivets 32, to ears 33 formed on plates 20.

The hooks 21 slide freely over and interlock with the edges of lips 14 of the frame upright and hold the plates 20, and associated parts, firmly in place and permit said plates to be readily removed and replaced without manipulation of any fastening members such as bolts or screws.

I claim as my invention:

1. In a wringer, a main frame comprising a base bar and end uprights, said uprights comprising an outer wall, side walls and in-turned vertical lips, and roller guards each comprising a slotted plate having hooks 60 along the slot slidably engaging the upright lips and clothes guides having upturned ends secured at their upper ends to said roller guards.

2. In a wringer, a main frame comprising a base bar and end uprights, said uprights comprising an outer wall, side walls and in-turned vertical lips, and roller guards each comprising a slotted plate having hooks along the slot slidably engaging the upright 70 lips and having a roller-guarding flange, and clothes guides having upturned ends secured at their upper ends to said roller guards.

In witness whereof, I have hereunto set my hand at Newton, Iowa, this 6th day of August, A. D. one thousand nine hundred and twenty six.

SIMON E. SCHROEDER.
